PERFORATING DEVICE FOR WELLS

William G. Sweetman, Houston, Tex.

Application June 15, 1948, Serial No. 33,062

2 Claims. (Cl. 102—20)

1

This invention relates to a perforating device for use in perforating well casings, especially in oil and gas wells.

Conventional perforating methods employ various forms of heavy metal guns which are arranged to fire projectiles through the casing into the surrounding formations for providing access passageways from the formations into the well casing for production of oil and gas. Due to space limitations and other conditions encountered particularly in deep wells, the effectiveness of such present gun perforating methods is considerably limited and present bullet-type guns are sometimes totally ineffective for penetrating well casings as well as the often thick layer of cement which is generally interposed between the casing and the face of the formations lining the well bore.

More recently, in an effort to overcome the disadvantages of the conventional gun perforation methods, particularly to provide greater penetrative force, there has been proposed the employment of charges of detonating explosives having hollowed ends facing the casing to be perforated. By thus employing the so-called "cavity" effect, perforation of the casing and the surrounding cement may be effected with or without the use of a projectile and greater perforating effectiveness may be obtained from such charges than is possible with the more conventional bullet-type gun.

As presently designed, guns using the cavity charges, employ a heavy metallic body, having the charges inserted therein and provided with detonating connections extending through the body and connected to an electric firing cable by which the tool is suspended and lowered into the well. Such gun bodies, particularly when they are designed to carry a plurality of perforating charges, as is required in most instances, are ordinarily of very heavy construction in order to be able to withstand the very heavy pressures generated by detonation of the charges without deformation of the body. Such gun bodies are relatively expensive to build and require careful machining to close tolerances for proper reception and sealing of the charges and firing connections, and their re-use, therefore, becomes essential for economic considerations. Also in the event such gun bodies should become broken or lost in a well, the well may become plugged thereby and because of their heavy metallic construction, they may be very difficult to drill-out or fish-out of the well.

Accordingly, it is a primary object of the pres-

2

ent invention to provide a charge carrying body for perforating guns which is of very simple and cheap construction; which may be completely disintegrated and expended in use without plugging the well; and which is highly effective in operation.

An important object is to provide a fully disintegrable gun body carrying cavity charges for perforating a well.

An additional object is the provision of a perforating gun body constructed of such a monolithic frangible material having a plurality of perforating charges embedded therein.

Another object is the provision of a perforating gun body constructed of a monolithic frangible material having perforating charges embedded therein and enclosed in a disintegrable fluid-tight casing constructed of non-metallic, flexible material, such as rubber, rubber-like plastics and the like, or of light easily shatterable metal.

A further object is the provision of a perforating gun having a body constructed of Portland cement or the like, in which the perforating charges are embedded during formation of the body.

Other and more specific objects and advantages of this invention will become apparent from the following detailed description when read in conjunction with the accompanying drawings which illustrate useful embodiments in accordance with this invention.

In the drawings:

Fig. 1 is an elevational view of a section of a well device in accordance with one embodiment of this invention;

Figs. 2 and 2a, together, comprise a longitudinal sectional view of the perforating device;

Fig. 3 is a cross-section through line 3—3 of Fig. 2;

Figs. 4 and 4a constitute a longitudinal sectional view of the perforating device, employing a somewhat modified form of firing train; and

Fig. 5 illustrates still another embodiment in accordance with this invention.

Referring to the drawings, the perforating device or "gun" in accordance with the illustrative embodiment of this invention comprises an elongated generally cylindrical structure, designated by the letter G, which is adapted to be inserted in a well. Structure G includes an elongated generally cylindrical body 10 having a head 11 at one end thereof and an end-piece 12 at the opposite end thereof. Body 10 is constructed of a cementitious, monolithic, frangible material to be described in greater detail hereinafter.

Head 11 will normally be constructed of a heavy metal such as steel and is adapted to be recovered for re-use, while end-piece 12 will ordinarily be constructed of a relatively brittle and easily shatterable material, such as cast aluminum, magnesium, or various solid plastics and which is expended in use. Extending longitudinally through body 10 are a plurality (two illustrated) of reinforcing rods 13 which are fastened to head 11, as by means of the threaded portions indicated at 14, or in any other suitable manner. The opposite ends of rods 13 extend through the opposite end of body 10 and are adapted to be slidably received in sockets 15 provided in end-piece 12. A plurality of perforating units, indicated generally by the numerals 16, are embedded in the material forming body 10, as will be described in greater detail hereinafter. Perforating units 16, which are generally cylindrical in outline, are disposed at right angles to the axis of body and are longitudinally spaced from each other and angularly oriented relative to each other, so as to produce any desired perforation pattern. One or more strips of flexible detonating cord 17, commonly known in the explosive art as "Prima-Cord," are threaded through the body and suitably connected to the explosive charges contained in the several units 16 in a manner well understood in the explosive art for providing a detonating train for the several charges. The ends of the "Prima-Cord" strips are led into head 11 through an axial passageway 18 which communicates with the interior of an internally threaded socket 19 carried by the outer end of head 11. A sealing plug 18a is provided at the entrance to passageway 18 to seal the end of the passageway about strips 17. Socket 19 is adapted to receive a threaded pin member 20 which is carried by the end of a lowering cable 21 in which is enclosed an electrical conductor lead 22. The latter is threaded through an axial passageway 23 in pin member 20, being suitably insulated therefrom, and connects to an electrical contact 24, which is mounted in the lower end of passageway 23. A tubular bushing 25 is screwed into the lower end of passageway 23 and carries on its upper end, insulated therefrom, an electrical contact 26 which is adapted to be put into conductive connection with contact 24 when bushing has been properly screwed or otherwise inserted into passageway 23. Bushing 25 is provided with an axial bore 27 in the lower end of which is inserted an electrical detonating fuse 28 of conventional form, which is connected by wires 29 to contact 26 and to the metallic portions of the pin member 20, which forms the ground for the firing circuit. When pin member 20, carrying the electrical connections and fuse 28, as described, is screwed into socket 19, fuse 28 will extend into passageway 18 into detonating relationship to the ends of the "Prima-Cord" strips. A pellet 30, composed of a suitable booster explosive, may be inserted between fuse 28 and the ends of the "Prima-Cord" strips to additionally assure the setting-off of the "Prima-Cord" strips upon detonation of the fuse. It will be understood that the fusing arrangement described is more or less conventional and is one of many conventional arrangements which may be employed for setting-off substantially simultaneously a string of explosive charges. Accordingly, it will be understood that the particular type of fusing or firing arrangement employed for setting-off the perforating charges is not, of itself, a critical feature of this invention.

Each of the perforating units 16 consists of a generally cylindrical shell 31 closed at its opposite ends and which will ordinarily be of sectional construction. In the form illustrated, the shells, which may be constructed of a metallic or non-metallic, easily shatterable material, such as aluminum, magnesium, or various plastics, are formed of two parts adapted to be joined together by means of a telescoping friction-type joint 32 intermediate the ends of the unit. Extending generally diametrically through one end of shell 31 is an opening 33 through which the "Prima-Cord" strip is threaded. Enclosed within each shell 31 is a charge 34 of detonating explosive of any of the well-known highly brisant types, such as trinitrotoluene, pentaerythritoltrinitrate, trimethylene trinitramine, and the like. These explosives are employed in highly compressed forms and are normally molded to the desired shape, being provided on the end facing the wall of the well to be perforated with a cavity 35 which may be generally conical, hemispherical or of other suitably hollowed shape, well known in the explosive art as adapted to concentrate the force of the detonation of the charge substantially along the axis of the cavity in the direction faced thereby. The hollowed end of the charge is preferably spaced inwardly a suitable distance from the end of the enclosing shell, depending generally upon the angle of the cavity and the degree of penetration desired, and a thin metallic liner 36 of shape complementary to that of the cavity is installed against the face of the cavity. A pellet 37 of a suitable booster explosive is inserted in the center of the opposite end of the charge contiguous to the "Prima-Cord" strip. An opening 38 is provided in the adjacent end of shell 31 for insertion of the pellet 37 and a threaded plug 39 is adapted to be screwed into opening 38 to close the latter and force the "Prima-Cord" strip into close contact with pellet 37 and the end of charge 34. The lengths of the shells 31 are generally made substantially equal to the diameter of body 10 so that the shell ends will be flush with the face of the body.

Body 10 is constructed of a cementitious monolithic material which is adapted to be cast or molded about the perforating charges, so that the latter and the "Prima-Cord" strips will be firmly embedded therein when the structure has been completed, and become, in effect, an integral part of the body. In every case, the material will be one which, when it has been allowed to harden, will have a crushing strength which will withstand the hydrostatic pressures which may be encountered in a well, and which, at the same time, will be highly frangible so that, upon detonation of the perforating charges, the detonating force will thoroughly shatter the body into small pieces which may be easily bailed or washed out of the well, or, even if left in the well, will not form a plug therein.

Materials which satisfactorily meet these requirements include various Portland cement mixtures, plaster of Paris, and the like. The particular mixes employed, the curing times, etc. will, of course, be varied to meet particular conditions under which the guns are to be run, the mixes and preparations conditions necessary to produce a monolithic material of the desired properties being well known by those skilled in the art.

The perforating device will normally be constructed in the following manner: Head 11 will be placed in the inverted position. Rods 13 will be screwed into the head and will extend upwardly.

If flexible wires are used in place of the stiff rods 13, the free ends of the wires will be supported in any suitable manner to hold them straight during construction of the gun. Perforating units 16 will then be attached to rods 13 in any suitable or convenient manner, as by means of wires 59 (see Fig. 3). Rods 13 form a supporting frame on which the charges are hung in any desired arrangement to produce the desired perforation pattern. "Prima-Cord" strips 17 are then threaded through openings 33 in the respective groups of shells and plugs 39 are inserted in the ends of the shells and made up tightly. The firing ends of the "Prima-Cord" strips are passed through plug 18a and into passageway 18, plug 18a being forced into the end of the passageway to seal it tightly. A cylindrical mold (not shown) of any suitable and conventional construction is then placed about the charge-carrying structure to enclose the latter with head 11 forming the bottom of the mold. A slurry of the material of which body 10 is to be constructed is then poured into the open top of the mold to fill the latter and bring the top of the body material to a point just below the outer ends of rods 13. The material is then allowed to set and harden to form the solid body 10 in which the perforating charges 16 will be firmly embedded and completely sealed therein. Rods 13 will provide reinforcement for the body to prevent its cracking in handling prior to detonation of the charges. Head 11 may be provided with a grooved socket, indicated at 51, to provide additionally firm attachment between head 11 and body 10. A metal end ring 52 may be embedded in the upper end of body 10 before it hardens to form a seat for end-piece 12 and to protect the outer edges of body 10 against cracking or spalling during handling prior to detonation. After body 10 has hardened to the desired degree, end-piece 12 will be placed over the protruding ends of rods 13 and pushed firmly against the end of body 10. The mold will then be removed from about the body and the primary gun structure will be complete.

Where the gun is to be employed in a well containing water or other well fluids which will subject the gun to substantial hydrostatic pressure, this invention provides an additional protective feature in the form of sleeve 40 which is adapted to form a fluid-tight casing for body 10 to prevent direct contact of any well fluid with the body or any of the explosive materials or connections carried thereby. Sleeve 40 may be constructed of any of the natural or synthetic rubbers or of any other flexible plastic material which, under external pressures will become tightly compressed about the body and thereby improve its sealing action. To additionally assure tight sealing by sleeve 40, head 11 and end-piece 12 may be provided with series of grooves or notches 41 and 42, respectively, in which the ends of sleeve 40 will be tightly compressed by means of suitable compression rings 43.

It will be understood that sleeve 40 need not be employed in cases where the perforating device is run in a well in which there is no fluid present. In cases where only relatively small hydrostatic heads are likely to be encountered, sleeve 40 may be merely a seal coat for the body and may be obtained by dipping or spraying body 10 with a suitable plastic material, which, when suitably dried, will form a fluid-impermeable coating for the body.

Sleeve 40 may, if desired, be constructed of thin metallic material, such as sheet aluminum, mag-

nesium, brass, or iron which will form a fluid-tight seal about body 10 but which will shatter or tear into relatively small pieces upon detonation of the charges.

5 The gun, constructed as described, is prepared for firing by inserting booster pellet 30 in passageway 18 between the ends of "Prima-Cord" strips 17, and then screwing pin member 20, carrying fuse 28 into socket 19. The device is then lowered 10 into the well opposite the point thereof in which perforations are to be made, and electric current, supplied from any conventional and suitable source on the surface, will be transmitted through cable 22 to detonate the charges. Upon detonation, the explosive forces will be directed by the hollowed ends of the charges against the casing and the surrounding well bore to effect the desired perforation thereof. At the same time, the explosive forces will act to completely 15 shatter body 10, as well as shell 31 which enclose the several charges, and will effectively disintegrate these parts. Similarly, end-piece 12 will be shattered, the latter being cored out at 44 to reduce its mass and provide a relatively thin section 20 in the center thereof which will give way easily under the shattering force of the explosion of the charges. All of the broken material will then fall to the bottom of the well and because of its rather complete disintegration may be easily 25 washed-out or bailed-out of the well, or easily ground up, if desired, by drilling. After detonation, head 11, which will usually be found to be unaffected by the detonation of the charges, will be withdrawn from the well and may be re-used 30 in the manner previously described in constructing another gun.

As indicated previously, the perforating charges will be arranged in any pattern desired prior to embedding them within body 10. It will be understood that any number of such charges may 35 be employed and may be spaced as closely or as widely as desired.

It will be understood that various more or less conventional support and reinforcing members, 40 such as wires, may be employed instead of the stiff rods 13 in constructing the gun.

From the foregoing, it will be evident that the perforating device constructed in accordance with this invention may be made very cheaply and, when set off, the body and perforating units will be thoroughly disintegrated without undesirable damage to the well. The device is found to be highly efficient in operation and by use of the cavity charges particularly will produce deep and effective penetration of well casing, the formations lining the well bore, and the usual cement liners normally placed between the casing and the well bore.

It will be understood that while the frangible 55 type gun body herein described is primarily designed for carrying cavity type perforating charges, such bodies may also be employed for carrying the more conventional bullet type charges.

Figs. 4 and 4a illustrate another embodiment in accordance with this invention, differing from that previously described only in the specific form of firing train employed to set off the perforating charges.

In this embodiment, an electrical detonating fuse 53, very similar to fuse 28 of the previous embodiment but normally having incorporated therein a pellet (not shown) of a suitable booster explosive, corresponding to pellets 37, is inserted 70 axially into the rear ends of charges 34. All of

the fuses for the separate firing units are connected in series by means of wires 54 to an electrical firing lead 55 which is threaded successively through openings 33 in the several explosive units. One end of firing lead 55 is connected to a firing electrode 56 which extends through passageway 18 into the bore of socket 19 where it makes contact with electrical contact 24 carried by the lower end of cable 22. Firing electrode 56 is, of course, suitably insulated from the walls of passageway 18. The opposite end of firing lead 55 is connected to a ground lead 57 which is grounded to head 11, as at 58.

This embodiment is assembled substantially in the same manner as that previously described with body 10 being poured or molded about the assembled firing structure and allowed to solidify into the final rigid structure. A sleeve 49 may then be applied, if desired, and the gun will be ready for receiving in a well and for operation in the manner previously described.

In still another modification, body 10 may be molded about a skeletal frame work comprising a plurality of receptacles for receiving the explosive charges connected together by suitable tubing for reception of the detonating train. Fig. 5 illustrates a portion of such a modification. Shells 31, in this modification, are open at one end and provided with an annular shoulder 61 inwardly of the open end to provide a seat for a sealing closure 62 having a packing ring 63 suitably seated in the periphery thereof and adapted to form a fluid-tight seal about the closure when the latter is inserted in the open end of the shell. The ends of opening 33 of each shell are connected by means of pieces of tubing 64 to the adjacent ends of similar openings of adjacent shells 31 in the series to be installed in the body so that, as will be readily understood, the shells will all thus be connected together into a skeletal frame work in which tubing 64 forms the connecting elements. Tubing 64 may be made of any suitable metal, such that it may be bent to the shape of the desired path for the detonating train. Or preformed plastic tubing may be employed for making the connections between the shells. This frame work will then be embedded in body 10 during molding, as previously described. After the body structure has thus been completed, the shaped explosive charges 34 with their hollow liners 35 will be inserted in the shells. A firing train, comprising either the "Prima-Cord" strips 17 or the wires 55 will then be threaded through tubing 64 and through each of the shells and placed in detonating contact with the charges 34, after which, closures 62 will be inserted to complete the firing assembly. A sleeve 40 may then be applied to body 10, if desired.

It will be further understood that various changes and alterations may be made in the details of the embodiment illustrated and described within the scope of the appended claims but without departing from the spirit of this invention.

What I claim and desire to secure by Letters Patent is:

1. A perforating gun for use in wells, comprising a metallic head member having a bore therein, a plurality of rods secured to said head member and extending downwardly therefrom, an end piece of easily shatterable material on the lower ends of said rods, a plurality of generally cylindrical shells positioned in vertically spaced relationship between said rods, means securing said shells in engagement with said rods with longitudinal axes of said shells disposed at substantially right angles to said rods, said head member, rods and shells constituting a substantially rigid assembly, an explosive charge positioned in each of said shells with a cavity in one end of the charge, a detonating train connecting said charges and extending into the bore of said head member, and a generally cylindrical body of monolithic cementitious material extending downwardly from said head member to said end piece and embedding said shells, detonating train and rods therein, said cylindrical body and said end piece being substantially completely shatterable under the force of explosion of said charges.

2. A perforating gun as defined in claim 1, having a liquid impervious sleeve surrounding said cementitious body and extending from said head member to said end piece.

WILLIAM G. SWEETMAN.
